(73) Assignee: **Motorola, Inc.**, Schaumburg, IL (US)

(57) CLAIM

The ornamental design for a battery housing, as shown and described.

DESCRIPTION

FIG. 1 is a top, front right isometric view of a battery housing showing our new design;

FIG. 2 is a front elevation view thereof;

FIG. 3 is a left side elevation view thereof, the right side being a mirror image;

FIG. 4 is top plan view thereof;

FIG. 5 is bottom plan view thereof; and,

FIG. 6 is rear elevation view.

The broken lines shown in FIGS. 1, 2 and 5 are shown to

indicate environmental features and are not claimed design.

The broken lines shown in FIG. 6 enclose an area that forms no part of the claimed design.

1 Claim, 5 Drawing Sheets
